UNITED STATES PATENT OFFICE.

DE NARD W. B. YOUNG, OF NARBERTH, PENNSYLVANIA, ASSIGNOR TO SOAP WORKS EQUIPMENT COMPANY, A CORPORATION OF PENNSYLVANIA.

APPARATUS FOR RAPIDLY AGING SOLIDIFIED PLASTIC ARTICLES.

1,316,262.

Specification of Letters Patent

Patented Sept. 16, 1919.

Original application filed January 10, 1916, Serial No. 71,150. Divided and this application filed March 27, 1917, Serial No. 157,636. Renewed July 12, 1919. Serial No. 310,502.

To all whom it may concern:

Be it known that I, DE NARD WILSON BUCKLEY YOUNG, a citizen of the United States, residing at Narberth, in the county 5 of Montgomery and State of Pennsylvania, have invented a certain new and useful Apparatus for Rapidly Aging Solidified Plastic Articles, of which the following is a specification, the same being a division of my 10 application serially numbered 71,150, filed January 10, 1916.

The present invention, broadly stated, relates to improved apparatus for rapidly aging solidified plastic articles and has 15 more particular relation to the rapidly aging of bars, blocks or cakes of soap and while the herein disclosed apparatus is adapted for the rapid aging of other solidified plastics, it is particularly fitted for the aging of what is 20 termed in the trade bar-soap, and for illustrative purposes, the following description will be restricted thereto.

In the manufacture of bar-soap, as now practised, soap, is first molded, then cut into 25 slabs and finally cut into elongated bars and placed upon racks where the soap remains for days at a time to dry or age, the length of time depending a great deal upon existing weather conditions. The bars of soap 30 thus dried or aged are then cut into cakes of proper size for commercial use. As thus manufactured, bar-soap is commercially unsatisfactory for a number of reasons. For instance by permitting soap to stand for 35 long periods of time, as above described, it develops a surface efflorescence or formation of fine, white, salt crystals. Further, undue penetration of dryness takes place thus causing shrinkage of soap and resultant loss of 40 weight. Still further, the bars of soap often become distorted or mis-shaped through long standing and perfume used for scenting the soap rapidly exudates. These and other disadvantageous results all tend to render the 45 method now practised exceedingly slow, unsatisfactory and expensive.

This invention has for its principal object to overcome these disadvantageous features and provide improved and novel apparatus 50 for the rapid aging of bar-soap whereby a more commercially valuable product is obtained than is now upon the market, in a much more rapid manner and at considerable less expense. A further object of the

present invention is to provide a new and 55 novel form of feed mechanism for endless conveyers whereby plastic articles may be continuously fed in abutting relation and in an unrestricted manner into the path of travel of the conveyers for removal in sequential relation. A further object of the 60 present invention is to provide safety means operative to be tripped by abutting yet unsevered pairs of said plastic articles as moved by the conveyer. Other and further 65 objects of the present invention reside in the providing of general details of construction and in the arrangement, connection and construction of parts as will hereinafter 70 more fully appear.

With these and other objects in view the invention consists of the improvements hereinafter described and finally claimed.

The nature, characteristic features and scope of the invention will be more fully 75 understood from the following description taken in connection with the accompanying drawings, forming part hereof and in which:

Figure 1 is a fragmentary view in section drawn to an enlarged scale of the feed attachment.

Fig. 2 is a sectional plan view taken upon the line 4—4 of Fig. 1, and

Fig. 3 is a fragmentary view in section 85 drawn to an enlarged scale of the feed attachment illustrating a movement hereinafter referred to.

For the purpose of illustrating my invention, I have shown in the accompanying 90 drawings one form thereof which is at present preferred by me, since the same has been found in practice to give satisfactory and reliable results, although it is to be understood, that the various instrumentalities of 95 which my invention consists can be variously arranged and organized and that my invention is not limited to the precise arrangements and organizations of the instrumentalities as herein shown and described. 100

In the drawings 10 designates a generally rectangular structure or housing preferably constructed of insulating material possessed of non-heat conveying properties, provided with a receiving chamber 11. Endless chain 105 belts 17—17 are present for substantially vertical travel through chamber 11.

Pivots connected to and suspended be-

tween the chain belts 17-17 are a multiplicity of soap holders or supports constructed so as to normally hang in a horizontal position during their passage through 5 the above mentioned compartment. Each soap-holder comprises a substantially U-shaped hanger preferably formed in one piece and embracing an apertured cross-piece 18 and a pair of uprights 19, slightly 10 bent outwardly at their upper ends and each terminating in a lug 20 apertured to receive a pivot pin for suspending the hanger with respect to the chain belts. Each upright is enlarged or reinforced at its bottom 15 for a purpose to presently appear. Disposed upon and at right angles to each cross-piece 18 is a one-piece saddle embracing a flat plate 21 having an upwardly extended lip 22 at its rear end having a pair 20 of soap engaging points 21' at its front end and having a central, depending, apertured lug 23. This apertured lug is detachably secured to the cross-piece of a hanger as by a bolt 24. The plate 21 is centrally 25 cut away as at 25 in order that little soap resisting surface be present and at the same time to lighten construction. The endless chain belts equipped with complementary soap-holders as above described will herein-after be termed the endless conveyer.

Feed.—Soap is first molded as usual, then slabbed and immediately introduced to a cutting machine (not shown in the drawings) and cut into bars, blocks or cakes 26. 30 From the cutting machine, the bar-soap is fed directly to compartment 11 by means of an apron 27. The soap as fed is of solidified plastic form, the surface of which is in a semi-crystalline, non-uniform condition. 35 Furthermore, the soap is in a vaporous or moist condition interiorly and exteriorly considered and it is essential that this moist condition be preserved indefinitely so that said soap retains its specific properties and 40 original weight. To that end, I treat soap to rapidly develop a superficial, uniform and translucent film or skin visibly free of crystalline salts and of an infinitesimal penetration. Thus, while the soap surface is 45 modified, the composition of the soap is not altered. The bars of soap are fed to compartment 11, in a positive manner in abutting positions by the apron 27. In practice, 50 a single bar of soap is fed forwardly upon 55 oppositely disposed sets of horizontal guides or finger pieces 28 fixed in the same plane with said apron top surface. The finger pieces form continuations of vertical guides 29 and are of proper size to hold or support 60 but a single cake. As the endless conveyer moves upward between said opposed sets of finger pieces 28, a bar of soap is bodily lifted from off said fingers by the saddle of a hanger and another bar of soap is moved 65 upon said finger pieces by the apron 27. It

sometimes happens that the cutting machine fails to entirely sever adjacent bars of soap so that when the saddle lifts its proper bar of soap a second bar is attached thereto. Should this condition continue, jamming of 70 the apparatus parts with likelihood of breakage thereof is present. To guard against this, I have provided immediately above the apron 27 a pivotal, horizontally disposed trip-plate 30 which carries a spring-pressed, 75 vertical member having at its free end a roller 31. Normally this roller engages the underside of a lip 32, which is fixed to the housing or casing 10 and this maintains plate 30 in position for tripping. When two 80 engaging bars of soap move upward, the outermost bar abuts against the underside of plate 30 with the result that the plate is moved around its pivot point so that the roller 31 rides outward or away from retaining lip 32. This movement of plate 30 is sufficient notice to the operator in charge to 85 immediately stop the operation of the apparatus. It may be here stated that the tension of the spring of the vertical member 90 carrying the roller 31 is such that should adjacent bars of soap but slightly adhere, the same may be caused to separate by said plate 30 without tripping thereof. In such case the bar of soap adhering to the upwardly moving bar is retained against upward movement.

It will now be apparent that I have devised a novel and useful apparatus which embodies the features of advantage enumerated as desirable in the statement of the invention and the above description and while I have in the present instance shown and described the preferred embodiment thereof which has been found in practice 100 to give satisfactory and reliable results, it is to be understood that the same is susceptible of modification in various particulars without departing from the spirit or scope of the invention or sacrificing any of 105 its advantages and that I have in mind the treating of plastic articles other than soap.

What I claim is:—

1. In apparatus of the character stated, feed mechanism embracing in combination 115 an endless conveyer provided with a plurality of free swinging holders, means operative in the path of travel of said holders for supporting a solidified plastic article, means for continuously feeding solidified plastic 120 articles in abutting relation toward said supporting means, means for guiding a holder to such a supported article and a safety element operative to be tripped by abutting yet unsevered pairs of said articles as moved by a single holder, said element being disposed in immediate juxtaposition to said supporting means.

2. In apparatus of the character stated, feed mechanism embracing in combination 130

- an endless conveyer provided with holders, each holder being designed to carry a solidified plastic article of predetermined size, means for feeding such articles to said conveyer, and means operatively positioned in immediate juxtaposition to the place of feeding said articles operative to be tripped by an article of a size of predetermined excessiveness as moved by a holder. 5 65
- 10 3. In apparatus of the character stated, feed mechanism embracing in combination an endless conveyer provided with holders, each holder being designed to carry a solidified plastic article of predetermined size, 15 means for feeding such articles to said conveyer, a fixed element above the feeding means and a movable element having cushioned roller relation with the underside of the fixed element, said movable element being designed to be shifted away from the fixed element by an article of a size of predetermined excessiveness as moved by a holder. 20 70
4. In apparatus of the character stated, feed mechanism embracing in combination an endless conveyer provided with a plurality of free swinging holders, oppositely disposed, spaced vertical guide pieces upon opposite sides of said holders for preventing swinging of the holders adjacent the apparatus feed, each guide piece terminating in a horizontal portion to form a fixed support, the inner ends of which are provided with vertical stops and means for feeding solidified plastic articles continuously in unrestricted, abutting relation toward said support whereby an individual article is always positioned upon the support irrespective of the location of an advancing holder. 30 75
5. In apparatus of the character stated, 40 feed mechanism embracing in combination an endless conveyer provided with a plurality of free swinging holders, oppositely disposed, spaced, vertical guide pieces upon opposite sides of said holders for preventing swinging of the holders adjacent the apparatus feed, the outer guide pieces being extended outwardly in a horizontal manner and the inner guide pieces being extended inwardly in a horizontal manner and then vertically the combined parts forming a support and a stop and means for feeding solidified plastic articles continuously in unrestricted, abutting relation toward said support, whereby an individual article is always 45 80
- 55 positioned upon the support irrespective of the location of an advancing holder. 50 85
6. In apparatus of the character stated, feed mechanism embracing in combination an endless conveyer provided with a plurality of holders, a fixed support constructed 55 for the travel therethrough of the holders, means for feeding solidified plastic articles of predetermined size continuously in unrestricted, abutting relation toward said support for removal by the holders in sequential relation and a safety element operative to be tripped by an article exceeding said predetermined size as moved by a holder. 65 90
7. In apparatus of the character stated, feed mechanism embracing in combination an endless conveyer provided with a plurality of holders, a fixed support constructed for the travel therethrough of the holders, means for feeding severed solidified plastic articles continuously in unrestricted, abutting relation toward said support for removal by the holders in sequential relation and a safety element operative to be tripped by an unsevered pair of said articles as moved by a holder. 70 95
8. In apparatus of the character stated, feed mechanism embracing in combination an endless conveyer adapted for substantially vertical travel provided with a plurality of free swinging holders each designed to carry an article of predetermined size and a safety element operative to be tripped by an article exceeding said predetermined size as moved by a holder. 80 100
9. In apparatus of the character stated, feed mechanism embracing in combination an endless conveyer, means for feeding articles of predetermined size to the conveyer, a fixed element above the feeding means and a movable element having cushioned, roller relation with said fixed element and designed to be shifted away from the fixed element by an article exceeding said predetermined size as moved by the conveyer. 90 105
10. In apparatus of the character stated, feed mechanism embracing in combination an endless conveyer, means for feeding articles of predetermined size to the conveyer, an element having a curved under face fixed above the feeding means, an element pivoted between the feeding means and the fixed element and a cushioned roller carried by the pivotal element normally engaging the under face of said fixed element, said pivotal element being designed to be shifted away from the fixed element by an article exceeding said predetermined size as moved by the conveyer. 100 110

In testimony whereof I have hereunto signed my name in the presence of two witnesses. 115
